UNITED STATES PATENT OFFICE

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY

TANK CAR TWIN TANK CONSTRUCTION

Application filed December 31, 1930. Serial No. 505,771.

This invention has to do with the art of tank car construction and is more particularly concerned with a type of car designed primarily for the transportation of liquefied 5 gases and the like.

The handling of gases in liquid form such as chlorine and sulphur-dioxide presents certain difficulties which must be adequately taken care of in order to provide for the 10 transportation and handling under safe conditions. It is important that the tanks containing the liquid gases be substantially strong and rigid to withstand any pressure that is likely to be created therein by the 15 gases. Moreover, the tanks must be thoroughly insulated against temperature changes so as to prevent the likelihood of increased pressure due to rises in temperature. Heretofore, there have been proposed certain 20 tank constructions for handling of liquefied gases, but these all more or less are characterized by being of comparatively small dimensions, and what are commonly 25 known as drums, it taking a comparatively large number of the tanks, or drums, to fill the dimensions of a single freight car. The present invention contemplates a tank car construction wherein a pair of tanks are disposed longitudinally of the car and constitute 30 a main body portion thereof. These tanks take up substantially all the space within the over-all dimensions of the car permitted by regulations and extend substantially 35 the full length of the car. An important feature of the invention is associated with the provision for mounting the tanks in position on the car. More in detail, I propose to avail of cradle structures under 40 each end of the tanks and which cradles are carried by the bolsters of the car. Intermediate the extremities of the car, the frame thereof is provided with a cross plate which is slotted to accommodate anchor plates 45 which are attached to the tanks themselves. The details of these connections will be described more fully hereinafter.

Another important phase of the present invention is the provision of means for supporting a run-way centrally over the tanks and therebetween at the upper surface of the

car. I propose to provide a casing which extends entirely around both of the tanks and which constitutes a support for the run-way, and insulation retaining means.

Another important object of the invention is associated with the provision for anchoring the straps for holding the tanks securely in position on the car frame. These straps are anchored at one end to the car bolster and pass over the tanks and have 55 their other end securely fastened to the center sill at a point spaced from the bolster. Other more detailed objects and advantages of the invention will in part become apparent and in part be hereinafter set forth as the 60 description of the invention proceeds.

For a full and more complete understanding of the invention reference may be had to the following description and accompanying drawings wherein similar reference characters designate corresponding parts and 65 wherein,

Fig. 1 is a side view taken on a plane midway between the tanks. This view is taken about on a plane represented by the lines 70 1-1 of Fig. 2.

Fig. 2 is a sectional view taken at right angles to Fig. 1. This view embodies sectional showings taken on two separate planes as represented by the lines 2 and 2a of Fig. 1.

Fig. 3 is an end view of the car, the tanks shown in dotted lines and

Fig. 4 is a top plan view of the car under-frame formed with the tanks omitted. In this view parts are broken away to permit of 80 showing on an enlarged scale.

Referring now to the drawings, a twin tank car made in accordance with the precepts of this invention may be described as comprising a center sill referred to generally as 85 A and from which extend adjacent each side thereof bolsters designated B. Connecting the bolsters and extending alongside of the car frame are side sills in the form of channel members C. These side sills extend the 90 full length of the car and are connected at the front end by an end sill member designated 10 which is also connected to the center sill as shown at 11. Each end of the car frame is braced by diagonal members 12 95 100

which are connected to the corners of the car as shown at 13 and to the center sill at the point where the bolsters B are joined thereto, this being indicated at 14 in Fig. 4.

5 In the illustrative embodiment, the center sill A is shown as comprising a pair of channel beams 15, which are disposed in opposed spaced relation and are connected by the cover plate 16 and the cross plate 21. Each 10 of the bolsters B comprises a pair of pressed diaphragms 17 which extend outwardly from each side of the center sill A. These diaphragms 17 are of general channel construction and are incorporated with the center sill 15 into a rigid structure through the medium of a top plate 18 and a bottom plate 19 which are riveted to the respective parts. These members 17 are of course connected at their outer ends to side sills C as shown at 20 as by 20 rivets. Intermediate the extremities of a car frame, the side sills C and the center sill A carry the central plate member 21 which is permanently attached to these parts as by rivets shown at 22. Cross bearers 9 of channel 25 form project from each side of the center sill A, connect with the side sills and constitute transverse supporting members for the central plate 21. This plate member 21 is formed with a series of spaced slots 23 for a 30 purpose to be hereinafter specified.

The cradles carried by each of the bolsters at each end of the car are of identical structure, so only one of them is here described for the purposes of this specification. This cradle includes block member 24 having a concave face 25 and which block is carried by a channel 26 that is secured to the supporting block 27. The latter is permanently fastened to the bolster B and side sill C as by rivets 40 shown at 28 in Fig. 2. This block and supporting structure is duplicated adjacent the center sill A in the form of block 29, channel 30, and supporting member 31. The concave face of the blocks 24 and 29 define the curvature of the cradle which may be carried out in the supporting block 32 by forming the latter with a curved seat designated 33 which conforms with the curvature of the concave face of the blocks. 45

50 A pair of tanks D is carried by the car frame structure above described and is seated at each end in the cradle. These tanks D are of duplicate structure and one of them may be described as including a metallic shell 34 which is covered by a comparatively thick layer of heat insulating material such as any suitable asbestos composition which is designated 35. This insulating material is cut away adjacent each end of the tank to 55 provide for contacting engagement between the concave faces of the blocks 24 and 29 and the shell 34. In order to provide for maximum diameters in the tanks D the shells 34 are spaced a very slight distance apart where 60 65 these tanks come together and the insula-

tion is cut away to provide for this close spacing, as is clearly shown at 36 of Fig. 2. It is important that these tanks be so disposed that they may be of the maximum diameter and still be within the dimensions permitted by regulations. 70

Midway the length of each tank D a dome 37 is provided and connected to the tank shell 34 and flanged as shown at 38. The insulation extends up about the dome 37 and under the flange 38 as is shown in Fig. 2 and is held in position by the annular flanged plate 75 70.

Each of the tanks D is provided near its upper end with a series of spaced supporting 80 brackets 39 for the support of an inclosing shell or casing which surrounds both tank shells. The brackets serve also as supports for the angle members 6 which support running board saddles hereinafter referred to. 85

These brackets may be connected directly to conventional tank bands as at 40 (Fig. 2) or to straps as 8 which surround the tank shells intermediate the tank bands. These straps are shown in dotted lines in Fig. 2 and 90 the connection of the brackets to the tank bands and straps permit riveting directly thereto and avoids the necessity of punching holes in the tank shells to receive rivets to connect the brackets directly to the tank shells. The brackets serve as supports for the casing 41 hereinafter more fully described and the extremities of the bands 8 may be connected together as shown in dotted lines in Fig. 2 at 7 to rigidly position the 100 bands about the tanks. These brackets extend through the insulation 35 and have their surfaces either flush with or extending slightly beyond the surface of this insulation. A casing 41 is disposed about the insulation 35 and extends entirely around both of the tanks when in their assembled relation and the inner surface of this casing 41 engages the supporting brackets 39. This casing 41 may be of a two-part construction including the parts 41a and 41b which are joined through the flange 42. Carried by the casing 41 between the tanks D and extending longitudinally of the car is a run-way 43 which is mounted on saddles 44 which are riveted to angles 6 which are connected to the casing 41 as shown at 45. These angle bars 6 serve to reinforce the casing in supporting the run-way. 110 115

The casing 41 extends the full length of 120 the tanks and at each end has connected thereto end plates 46 which cover the extremities of the tanks D. Ladders 47 may be located at each end of the car and constitute substantial continuation of the run-way 43. 125 These ladders are connected at their lower extremities to the platform 49, which in turn is carried by the underframe.

Referring now more particularly to the 130 manner in which the tanks D are anchored

to the car, it is notable that each of the tanks has connected thereto as by rivets 50 a pair of spaced longitudinally extending anchor plates 51 having flanges 52 through which the rivets 50 extend. These anchor plates 51 are located centrally of the car and extend downwardly and pass through the slots 23 in the plate 21. They are permanently connected to the plate 21 by angle bars 53 which are disposed on the under face of the plates and which are riveted to the plates 51 and cross plate 21. Cooperating with these angle bars 53 are upper angle bars 54 constituting parts of a tank anchor. One flange of each of the angles 54 is fastened to the plate 51 as shown at 55 while the other flange rests upon the upper face of the plate 21. This connection centrally of the car is repeated for each of the tanks D and serves to permanently hold them in position on the underframe. Conventional tank bands 59 extend about the shell 34 and engage therewith. These straps are disposed in cut away portions of the insulation 35 and have their ends anchored near the side and center sills respectively. This is brought out clearly in Fig. 2 which shows one of the straps 59 connected to the side sill as at 60 while the other end is connected with the center sill as shown at 61. This connection with the center sill is off-set from the bolster as illustrated in Fig. 1, to provide for a rigid and permanent assembly.

It is evident from the foregoing that I have provided a twin tank construction in which the tanks are compactly arranged to provide for maximum diameters of the tanks and which are rigidly and positively mounted on the car frame in a manner providing for suitable heat insulating effects which render the tanks particularly adaptable for the handling of liquefied gases.

While a preferred specific embodiment of the invention is hereinbefore set forth, it is to be understood that I am not to be limited by the exact construction illustrated and described because various modifications of these details may be provided in putting the invention into practice within the purview of the appended claims.

50. What is claimed is:

1. In a tank car construction, the combination with a car frame of a pair of insulated tanks carried by the frame and extending lengthwise of the car frame, means for anchoring the tanks to the car frame centrally of the car; additional means adjacent each end of the car for holding the tanks in position on the frame and a casing surrounding the pair of tanks and supported thereby.

60. 2. In a tank car construction, the combination with a car frame of a pair of insulated tanks disposed thereon and extending longitudinally of the car, permanent fastening members carried by each of the tanks intermediate their extremities and connected to

the car frame centrally of the car, and a casing surrounding the pair of tanks and supported thereby.

3. In a tank car construction, a combination with a car frame of a pair of insulated tanks disposed thereon and extending longitudinally of the car, a floor on said frame, permanent fastening members carried by each of the tanks intermediate their extremities and connected to the floor centrally of the car, said members comprising vertically extending plates which are connected to said floor by angle bars and a casing surrounding the pair of tanks and supported thereby.

4. A tank car of the character described, comprising, a pair of tanks extending longitudinally of the car, brackets mounted on the tanks, heat insulating material on said tanks, means surrounding the pair of tanks and supported by said brackets for retaining the insulating material in position, said last-mentioned means also constituting a support for a run-way.

5. A tank car of the character described, comprising, a pair of tanks extending longitudinally of the car, bands clamped to the tanks, brackets secured to said bands, heat insulating material on said tanks, means surrounding the pair of tanks and supported by said brackets for retaining the insulating material in position, said last-mentioned means also constituting a support for a run-way, a car frame and means for anchoring the tanks in assembled position on the car frame.

6. A tank car of the character described, comprising, a frame consisting of a center sill, bolsters adjacent each side of the center sill and crossbearers, a plate secured to said bearers, cradle structures carried by each of the bolsters on each side of the center sill, and a pair of tanks seated in said cradles and extending longitudinally of the car and means secured to said plate and to said tanks for anchoring the tanks to the car frame.

7. A tank car of the character described, comprising, a frame consisting of a center sill, bolsters adjacent each side of the center sill and crossbearers, a plate secured to said bearers, cradle structures carried by each of the bolsters on each side of the center sill, and a pair of tanks seated in said cradles and extending longitudinally of the car, said tanks including shells which are spaced a slight distance apart, and insulation covering the shells, said insulation being cut away to accommodate close positioning of the shells and means secured to said plate and to said tanks for anchoring the tanks to the car frame.

8. A tank car of the character described, comprising, a frame consisting of a center sill, bolsters adjacent each side of the center sill and crossbearers, a plate secured to said bearers, cradle structures carried by each of

the bolsters on each side of the center sill, a pair of tanks seated in said cradles and extending longitudinally of the car, said tanks including shells which are spaced a slight 5 distance apart, insulation covering the shells, said insulation being cut away to accommodate close positioning of the shells and means disposed centrally of the tanks for securing them to said plate in position on the car 10 frame.

9. A tank car construction of the character described, comprising, a frame consisting of a center sill, end bolsters and side sills, a cross plate connected to said sills and center 15 sill intermediate the ends of the car, said cross plate being formed with slots, a pair of tanks carried by the frame, vertically extending anchor plates rigidly connected to the tanks and extending through said slots 20 in the cross plate and means for connecting said anchoring plates to the cross plate.

10. A tank car construction of the character described, comprising, a frame consisting of the center sill, end bolsters and side sill, a cross plate connected to said side sills and center sill intermediate the ends of the car, said cross plate being formed with slots, a pair of tanks carried by the frame, vertically 25 extending anchor plates rigidly connected to the tanks and extending through said slots in the cross plate and means for connecting said anchoring plates to the cross plate, said means consisting of angle bars disposed above and below the cross plate and connected to the 30 anchoring plates.

11. In a tank car construction, a car frame consisting of a center sill, side sills and end bolsters, a cross plate connected to said side 40 sills and center sill, a plurality of tanks carried by the car frame, anchor members secured to said tanks and said plate and straps for holding the tanks in position on the car frame, said straps having one extremity anchored to the side sill and the other to the 45 center sill at a point offset from the bolster.

12. A tank car comprising, a car frame, a plurality of insulated tanks extending longitudinally of the car and carried by the frame, 50 a casing extending about and supported by said tanks, and a longitudinally extending run-way carried by the casing and disposed centrally of the car.

13. A tank car comprising, a car frame, a plurality of insulated tanks extending longitudinally of the car and carried by the frame, a casing extending about and supported by said tanks, a longitudinally extending run-way carried by the casing and disposed centrally of the car, and ladders at 55 each end of the car communicating with the run-way.

14. In a multi-unit tank car, a frame comprising side sills, center sill and cross members, a floor sheet extending between the side 60 sills and provided with spaced pairs of lon-

gitudinal slots arranged on either side of the center sill, tank anchor members extending through said slots and secured to the floor sheet, and tanks supported by the pairs of anchor members.

15. In a multi-unit tank car, a frame comprising side sills, center sill and cross members, spaced pairs of cradles on either side of the longitudinal axis of the car, a pair of tanks supported by said cradles, anchor members secured to said tanks and certain of said cross members for anchoring said tanks to said frame, a single casing surrounding the pair of tanks and a running board arranged above the tanks and supported by said casing intermediate the tanks.

16. In a multi-unit tank car, a frame comprising side sills, center sill, crossbearers and end bolsters, a floor plate extending between the side sills and crossbearers, said plate being secured to the side sills and crossbearers and being provided with slots, tank anchor members extending through the slots and secured to said floor, a plurality of tanks secured to said members, and a casing surrounding the tanks and supported thereby.

17. In a multi-unit tank car, a frame comprising side sills, center sill, crossbearers and end bolsters, cradles on said bolsters, a floor plate extending between the side sills and crossbearers and secured thereto, said plate being provided with slots arranged on either side of the longitudinal axis of the car, tank anchor members extending through the slots and secured to said floor, a pair of tanks arranged longitudinally of the car and supported by said cradles and secured to said members.

18. In a multi-unit tank car, a frame comprising side sills, center sill, crossbearers and end bolsters, cradles on said bolsters, a floor plate extending between the side sills and crossbearers and secured thereto, said plate being provided with slots arranged on either side of the longitudinal axis of the car, tank anchor members extending through the slots and secured to said floor, a pair of tanks seated in said cradles and extending longitudinally of the car, said tanks being secured to said anchor members, heat insulating material on said tanks, a casing surrounding the pair of tanks and supported thereby, and a running board arranged above the tanks and supported by said casing intermediate the tanks.

In witness whereof I have hereunto set my hand.

VICTOR WILLOUGHBY.
